UNITED STATES PATENT OFFICE.

MCERTON M. WEIL, OF SCRANTON, PENNSYLVANIA, ASSIGNED TO SAMUEL H. FRANK,
OF SCRANTON, PENNSYLVANIA.

COLLAR.

Application filed April 12, 1932. Serial No. 334,607.

To all whom it may concern:

Be it known that I, MCERTON M. WEIL, a citizen of the United States, residing at Scranton, in the county of Lackawanna and State of Pennsylvania, have invented an Improvement in Collars, of which the following is a specification.

This invention relates to a collar and more particularly to that form of collar adapted to have a band and a flap overlying the same. The invention is furthermore particularly adapted to the type of collar termed soft collars; although the invention is in no wise limited to this particular type of collar as it may be employed also in the well known form of starched stiff collars. Heretofore soft turnover collars have been made in various manners in attempts to make the same conform to the neck of the wearer and to retain their shape. For example, soft turnover collars have been woven to provide a weakened line, preferably a curvilinear line along which the parts of the collar are folded to cause the same to conform to the neck and retain their shape. In this and other similar forms of collars, however, so far as I am aware, it has been necessary heretofore to cut the entire collar or a portion thereof from a strip or other form of material in which the same is woven and to connect the parts of the collar along the edges thereof by a suitable binding or otherwise.

In carrying out my invention I obviate the necessity of cutting the collar in its entirety from the fabric by weaving the material in strips with the edges thereof so shaped that collars may be cut therefrom by transversely severing the said strips. This obviates the necessity of binding the parts of the collar along their longitudinal edges. Also in carrying out the invention the material is so woven that in each collar section there are provided reinforced portions for strengthening the collar for retaining the collar in position on the neck of the wearer and for providing a groove or channel for the scarf worn with the collar; and furthermore in the collar made in accordance with my invention the flap member is adapt-

ed to be turned over on either side of the band member to make the collar reversible. The collar made in accordance with this invention is similar in many respects to that shown and described in my copending application Serial No. 554,606 executed under like date herewith and in which the material is woven in a tubular form. In the present case, however, the band member of the collar is preferably woven solid and the flap member only is woven tubular, the flap member being adapted to turn in either direction on the line dividing the same from the band member so as to make the collar reversible, and the collar made in accordance with this invention will be hereinafter more particularly described.

In the drawing:

Fig. 1 is a plan of a collar made in accordance with this invention.

Fig. 2 is an enlarged section on line 2--2, Fig. 1.

Fig. 3 is a section on line 3--3, Fig. 1.

Fig. 4 is a plan of another form of the invention.

Fig. 5 is an enlarged section on line 5--5, Fig. 4, and

Fig. 6 is an enlarged section on line 6--6, Fig. 4.

Referring to the drawings and particularly to Figs. 1, 2 and 3, the collar made in accordance with this invention comprises a band member 10 and a flap member 11. The band member 10 is preferably woven solid and the flap member 11 is preferably woven tubular and the collar material is woven in a continuous strip so as to be produced in one part and the collar sections are woven to shape by suitably adjusting the parts of the loom in which the strips of material are woven. It will be understood that the band section may be woven of a given texture and the flap member of another texture, or both the band and flap members may be made of material of the same texture. The line of division between the band member and the flap member is indicated at 12 and the flap member is adapted to turn on this division line 12 so as to be folded in either direction against the 100

band member thereby making the collar reversible.

By suitably crowding the warps or otherwise in weaving the material, the edge of the band member as indicated at 13 is reinforced or strengthened to afford the collar additional strength along the line of greatest tension and wear. Similarly the edge section of the flap member is reinforced as indicated at 14 to cause the collar to retain its shape when in use. Furthermore the reinforced section 13 of the band member may be provided in the weaving with suitable threads representing stitches 15 and similar and corresponding threads may be provided in the weaving in the reinforced section 14 of the flap member 11.

After the material is thus woven the strips are cut transversely by a suitable tool along the line indicated at 17 or otherwise to form each individual collar. The extremities 18 and 19 of the tubular flap section 11 are then inturned and connected by suitable lines of stitching. As clearly illustrated in Fig. 2 there is a line of stitching 20 extending through these inturned end sections and also through the outer sections of the tubular flap member and an additional line of stitching indicated at 21 which extends only through the sections of the tubular flap member adjacent the extremities of the inturned ends of the fabric. This additional line of stitches indicated at 21 thus acts as a base or reinforcement for the ends of the inturned portions, and also prevents the same from fraying or becoming unraveled. The ends of the band member are preferably stitched as indicated at 22 in any suitable manner to prevent these edges from fraying or becoming unraveled. For example, this stitch may be the well known button hole stitch.

In the band member 10 there is a section indicated at 23 and 24 for reinforcing the same. This section is made in the same manner as the reinforced sections at the edges of the band member and the flap member, and not only increases the strength of the band member but also acts in conjunction with the reinforced section of the band member to provide a channel or groove for the scarf which may be worn with the collar. The collar is also provided with the usual and customary button holes indicated at 25 and 26.

Referring to Figs. 4, 5 and 6, the form of the collar illustrated is the same as that shown and described in the other form of the invention, with the exception that the end portions of the band member 10' instead of being woven solid are woven tubular as indicated at 27 and 28 so that the entire end portions of both members of the collar are of a tubular weave construction. In this structure the strips of material are cut transversely into the collar sections and the end

portions thereof turned in and stitched in the same manner as that hereinbefore described for finishing the end sections of the tubular flap member 11. Moreover, in this form of the invention in order to stiffen and strengthen the tubular end sections of the band member I may employ inserts indicated at 29 made of any suitable material and placed between the parts forming the tubular end sections of the band member 10'. These insert members 29 may be secured in position by the same lines of stitching which connect the inturned extremities of the tubular sections at the ends of the band member.

From the foregoing it will be understood that the collar made in accordance with this invention is woven to shape in one piece with the band section preferably woven solid and the flap section woven tubular and adapted to be folded over on either side of the band member to make the collar reversible, and the parts of the collar are reinforced in such a manner as to strengthen the same at the line of greatest tension and wear to cause the parts of the collar to retain its shape in use and to provide for a groove or channel for the scarf which may be worn with the collar.

I claim as my invention:

1. A collar comprising a neck band member and a flap member, the said members being woven in one piece, with a part of the flap member woven solid and provided in the weaving with a reinforced longitudinal edge, the flap member being woven tubular with the transverse edges thereof inturned and stitched to form the ends of the flap member of the collar.

2. A collar comprising a neck band member and a flap member, the said members being woven in one piece with a part of the neck band member woven solid and the flap member woven tubular and provided in the weaving with a reinforced longitudinal edge, the transverse ends of the said flap member being inturned and stitched to form the ends of the flap member of the collar.

3. A collar comprising a neck band member and a flap member, the said members being woven in one piece, with a part of the flap member woven solid and provided in the weaving with a reinforced longitudinal portion to determine the fold line, with the flap member woven tubular with the transverse edges thereof inturned and stitched to form the ends of the flap member of the collar.

4. A collar comprising a neck band member and a flap member, the said members being woven in one piece, with a part of the neck band member woven solid and the flap member woven tubular, with reinforced sections provided in the weaving and extending along the longitudinal edges of the neck band and flap members, with the transverse edges of the flap member inturned and

stitched to form the ends of the flap member of the collar.

5. A collar comprising a band member and a flap member, the said members being woven in one piece, with a part of the band member being woven solid and provided in the weaving with a reinforced longitudinal edge and reinforced section for deter-

mining the fold line, the said flap member being woven tubular and provided in the weaving with a reinforced longitudinal edge, with the transverse edges thereof inturned and stitched to form the ends of the flap member of the collar.

Signed by me this 7th day of April, 1922.

MORTON M. WEIL.
